US00D716883S

(12) United States Design Patent
Stokke et al.

(10) Patent No.: US D716,883 S
(45) Date of Patent:  Nov. 4, 2014

(54) GOLF CLUB HEAD

(71) Applicant: Karsten Manufacturing Corporation,
Phoenix, AZ (US)

(72) Inventors: Ryan M. Stokke, Phoenix, AZ (US);
Xiaojian Chen, Phoenix, AZ (US);
Martin R. Jertson, Phoenix, AZ (US);
Cory S. Bacon, Scottsdale, AZ (US)

(73) Assignee: Karsten Manufacturing Corporation,
Phoenix, AZ (US)

() Term: 14 Years

(21) Appl. No.: 29/492,280

(22) Filed: May 29, 2014

(51) LOC (10) Cl. 21-02

(52) U.S. Cl.

USPC D21/747

(58) Field of Classification Search

USPC D21/747-751; 473/324-331, 350

See application file for complete search history.

OTHER PUBLICATIONS

Michael R. Nicolette, et al., "Golf Club Head," U.S. Appl. No. 29/455,105, filed May 16, 2013.

Primary Examiner — Mitchell Siegel

(74) Attorney, Agent, or Firm — Karsten Manufacturing Corp.

(57) CLAIM

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a front view of the golf club head of FIG. 1;

FIG. 4 is a rear view of the golf club head of FIG. 1;

FIG. 5 is a top view of the golf club head of FIG. 1;

FIG. 6 is a bottom view of the golf club head of FIG. 1;

FIG. 7 is a right view of the golf club head of FIG. 1; and,

FIG. 8 is a left view of the golf club head of FIG. 1.

The broken line showing is included for the purpose of illustrating and forms no part of the claimed design.

1 Claim, 4 Drawing Sheets
